UNITED STATES PATENT OFFICE.

FREDERICK J. MURRAY, OF NATICK, MASSACHUSETTS.

OIL-VAPORIZER FOR THE LUBRICATION OF STEAM-CYLINDERS.

1,178,936.

Specification of Letters Patent. Patented Apr. 11, 1916.

Application filed March 10, 1913. Serial No. 753,395.

To all whom it may concern:

Be it known that I, FREDERICK J. MURRAY, residing at Natick, in the county of Middlesex and State of Massachusetts, have invented a new and useful Oil-Vaporizer for the Lubrication of Steam-Cylinders, of which the following is a specification.

My invention relates to a vaporizer attached to the main steam pipe supplying steam to an engine cylinder receiving oil from a lubricator and the objects of my improvement are the heating, breaking up, and vaporization of the oil before it reaches the steam in the main steam pipe by the use of a steam jet which draws the oil into the vaporizer, drives it against the closed end causing it to rebound and collide with other particles of steam and oil thus breaking up and allowing it to be fed close to the cylinder and insuring a better distribution of the oil at the valves and in the cylinder and consequently reducing the consumption of oil. I attain these objects by the mechanism illustrated in the accompanying drawing in which—

Figure 1 is a general drawing showing the position of the vaporizer in an oil feed system. Fig. 2 is a vertical section through the vaporizer. Fig. 3 is a cross section on the line 1 and 2. Fig. 4 is a cross section on the line 3 and 4.

Similar letters refer to similar parts throughout the several views.

Referring to Fig. 1, A is a steam pipe supplying the lubricator and vaporizer with steam from the main steam pipe E. B is any lubricator suitable for lubricating steam engine cylinders. C is the oil pipe from the lubricator to the main steam pipe E. D is the vaporizer connected to the steam pipe A and oil pipe C with the end inserted in the main steam pipe E.

Referring to Figs. 2, 3, and 4 a is an elbow through which the steam enters the nozzle b drawing the oil through the elbow d into the chamber c heating and vaporizing it in c and f and forcing it against the closed end and out through the holes h in the pipe f into the main steam pipe E.

50 I claim:

1. In an oil feeding system for a steam cylinder, a lubricating pipe, an atomizer comprising a straight tubular casing adapted to extend into the steam main, a steam pipe connected to and extending through the end of said casing and ending in a nozzle discharging beyond the lubricant pipe connected to the side of said casing substantially as described.

2. In an oil feeding system for a steam cylinder an atomizer consisting of an atomizer casing adapted to extend into the steam main, a lubricant pipe connected to said casing and a steam pipe connected to and extending through said casing and ending in a nozzle beyond said lubricant pipe connection substantially as described.

3. In an oil feeding system for a steam cylinder, an atomizer, comprising a tubular atomizer casing adapted to extend into the steam main, said projection into the main having its sides perforated and end closed, a lubricant pipe from a receptacle connected to the side of said casing and a steam pipe connected to, and extending into the end of said casing, ending in a nozzle beyond said lubricant pipe connection substantially as described.

4. In an oil feeding system for a steam cylinder a vaporizer attached to the main steam pipe consisting of a straight tubular chamber enlarged at one end, the smaller end extending into said steam main having the under side perforated and the end closed; a lubricant pipe from a receptacle connected to the side of said large chamber and a steam pipe connected to and extending into the end and nearly through said larger chamber and beyond the lubricant pipe substantially as described.

5. In a system for feeding oil to the valves and cylinders of a steam engine the combination of (1) a lubricant receptacle (B), (2) a lubricant pipe leading from the receptacle (C), (3) a steam pipe (A) and (4) an atomizer having a steam nozzle (b) a closed end (g) and holes (h) extending into the steam main and connected to the steam and lubricant pipes substantially as set forth.

6. In an atomizer or vaporizer for lubricating steam cylinders, the combination of a straight tubular casing, having one end enlarged and the other adapted to extend into the steam main, a lubricant pipe connected to the side of the larger end of said casing and a steam pipe extending through the larger end of said casing and ending in a nozzle beyond the lubricant pipe for the purposes set forth substantially as described.

7. In an atomizer or vaporizer for lubricating steam cylinders, the combination of

a straight tubular casing enlarged at one end; the other end perforated on the under side and closed and adapted to extend into the steam main with a lubricant pipe connected to the side of the larger end of said casing and a steam pipe connected to and extending longitudinally into said larger end beyond the lubricant pipe connection for the purposes set forth substantially as described.

8. In a system for feeding oil to the valves and cylinders of a steam engine, the combination in a straight tubular vaporizer casing having one end enlarged and connected at the side to an oil pipe from a lu-

bricant receptacle and the other closed and adapted to extend into the steam main with a steam nozzle fed by a steam pipe extending longitudinally into said larger chamber and perforations in the under side of the closed end of the casing inside the steam main for the purposes set forth substantially as described.

In testimony whereof I have affixed my signature in the presence of two witnesses. 25

FREDERICK J. MURRAY.
